(57) **CLAIM**

The ornamental design for a stand for electronic device, as shown and described.

DESCRIPTION

FIG. 1 is a front perspective view of a stand for electronic device showing our new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another front perspective view thereof shown in an environment of use.

The broken lines throughout the drawing figures depict portions of the stand for electronic device that form no part of the claimed design. The broken lines and regions bounded by broken lines form no part of the claimed design.

1 Claim, 9 Drawing Sheets
